WITNESS:

UNITED STATES PATENT OFFICE.

FRED ALBERT, OF MEXICO, MAINE.

COAL CART.

Application filed October 7, 1922. Serial No. 593,035.

To all whom it may concern:

Be it known that I, FRED ALBERT, a citizen of the United States, residing at Mexico, in the county of Oxford and State of Maine, have invented new and useful Improvements in Coal Carts, of which the following is a specification.

My present invention has reference to an improved coal wagon, and has for its object 10 to produce a vehicle of this character provided with means whereby coal may be delivered at the rear and at the sides thereof in small quantities, as when the same is to be received in baskets or at a small flow, 15 as when the coal is to be delivered through chutes or spouts, and further whereby when the coal is to be dumped in a volume without necessitating the employment of shovels or other means for scraping the coal from the 20 wagon or cart.

To the attainment of the foregoing, and other objects which will present themselves as the nature of the invention is better understood, reference is to be had to the drawings which accompany and which form part 25 of this application.

In the drawings:—

Figure 1 is a side elevation of a coal wagon in accordance with this invention.

30 Figure 2 is a rear elevation thereof.

Figure 3 is a top plan view thereof.

Figure 4 is a sectional view on the line 4—4 of Figure 3.

Figure 5 is a sectional view on the line 35 5—5 of Figure 1.

Figure 6 is a side elevation showing the body tilted to dumping position.

The wagon body 1 is supported in the usual manner by the bolsters for the axles 40 of the front wheels 2 and the rear wheels 3, a tongue or shaft being connected to the hounds of the front axle for the draft animal. Of course, the vehicle may be motor propelled, if desired.

45 The body 1 has its bottom inclined downwardly from its front to its rear, the sides of the body being also inclined upwardly from the center to the sides of the body, as indicated by the numeral 4, while the body 50 at the front thereof, is inclined downwardly to the center of the sides, this portion of the front being substantially V-shaped in plan and is indicated in the drawings by the numeral 5. The front bolster is provided with

55 an inwardly extending portion in the nature of a plate 6, and this plate has a central

opening 7 therethrough through which passes an arched rack 8 that has its upper end secured to the under face of the V-shaped front portion 5 of the bottom of the body. On the rear of the bolster, slightly above the plate 6 there is journaled in suitable bearings a shaft 9 that has secured thereto a pinion 10 which is in mesh with the teeth of the rack 8. On the shaft there 65 is a ratchet wheel 11 engaged by a spring dog 12 secured to the bolster whereby the shaft is sustained against accidental turning. The shaft has a squared end extension to receive the squared socket of a crank handle 70 13. The shaft is permitted to turn in one direction whereby to swing the front of the body upwardly, the said body being fulcrumed from the rear axle thereof. The dog is moved out of engagement with the 75 ratchet wheel when the shaft is to turn in an opposite direction.

On the plate 6, and contacting with the smooth face of the rack 8 there is a roller 14 journaled in suitable bearings on the said 80 plate.

The rear end of the body 1 is closed by a gate 15 which has at its upper corners extending trunnions 16 journaled in bearings 17 at the upper edges of the sides of the 85 body. The gate has its lower edge substantially V-shaped to engage with the angle side walls 4 of the bottom of the body.

The gate 15, at the lower center thereof is provided with a rectangular opening, and 90 closing this opening there is a door 18 which is hinged to the gate in a line with the upper wall provided by the said opening. The door 18 projects beyond the lower edge of the gate, and the said projecting end of the 95 door has its walls inclined from its sides downwardly toward its center, the said walls being also beveled inwardly. For distinction, the lower end of the door is indicated by the numeral 19, and the same is centrally 100 formed with a projecting tongue 20. The bottom of the wagon body, at the rear end thereof is provided with a depression 21, complementary to the outer or lower end of the door and with a notch 22 to receive the 105 tongue 20 therein.

By reference to the drawings, it will be noted that the rear end of the body, except for the opening therein is of a substantially rectangular formation, the same being 110 built out on both the sides and the bottom thereof, and on the said rear end there is

arranged the body portion of the body plate 22' of a spout 23 of a cross sectional shape complementary to the lower end of the door, and the depression in the end receiving the door. The plate 22' below the spout is provided with vertically disposed elongated openings, and through these openings there are passed the shanks of headed drive members 24. The plate, at the upper ends thereof is formed with projecting fingers 25, the said fingers being received through guide rails 26 in the wagon end. Pivotally secured to the center of the substantially V-shaped spout 23, and also pivoted to one of the headed members 24 there is a lever 27. The lever, from its connection with the element 24, is bent at a right angle, so that one edge thereof will engage with a toothed rack bar 28 on the end of the wagon body. When the lever is brought to engage with one of the teeth of the rack 28, the spout will be moved to cover the tongue of the door 18, and the fingers 25 of the said spout will be likewise moved to contact with the end gate. When the lever is swung to engage a second notch in the rack 28, the spout will be moved downwardly a sufficient distance to uncover the tongue of the door 18, but the fingers 25 will still contact the end gate 15. The door is provided with a suitable knob or handle 29, and may be swung open while the end gate is still locked so that a quantity of coal will gravitate along the inclined bottom of the body through the door opening and be directed by the spout 23 into a basket or the like when a small quantity of coal is to be delivered. In a like manner, a trough may be arranged upon the spout so that the coal from the wagon can be directed a determined distance away therefrom. Should it be found that all of the coal will not properly flow through the trough, the shaft 9 may be operated to raise the inner end of the body. When the coal is to be deposited in a load from the body, the lever 27 is further swung to bring the fingers 25 out of contact with the end gate, when the end gate may be swung to fully open position or may be forced to such position by the contact of the coal therewith. To facilitate the opening of the end gate, the latter is provided with a handle 30.

The extending side portions of the end of the body provide the same with opposed compartments 31 and 32 respectively. These compartments have their outer or face portions open, the same, however, being normally closed by removable sliding doors 33. The bottom of the compartments are also partly open, as at 34, the purpose of which will be presently set forth. The inner walls of the respective compartments are inclined from their outer or face portions to the center thereof, and for distinction

these inner walls are indicated by the numeral 35, the said walls terminating with the center of the bottom and being extended a suitable distance therebelow. The bottom of the body is provided with openings 70 communicating with the compartments 31 and 32, and the walls of these openings are complementary to the opposed front and rear walls of the compartments. These openings are closed by doors 36 and 37 75 whose opposed walls are complementary to those provided by the openings in the wagon bottom. The doors, however, project beyond the sides of the wagon body and are received against the inclined upper walls 38 of the respective compartments 31 and 32. Preferably, the doors 36 and 37 are beveled upon their lower faces at their upper corners, so that when the same are received in the openings 34 in the lower walls of the compartments, the same provide an unrestricted inclined plane, whereby coal from the wagon body may be delivered through either side at the ends thereof. A pinch bar or suitable implement may be inserted through the openings in the lower walls of the compartments to contact with the doors and swing the same to closed position, and when in such position, the said doors are engaged by latches 39 provided with operating handles 40 arranged on the outer walls of the respective compartments 31 and 32.

It is thought that the foregoing description, when taken in connection with the drawings will fully set forth the construction and advantages of the improvement to those skilled in the art to which this invention relates, but it is to be understood that the invention is not to be restricted to the precise structural details herein set forth, as I may, in the manufacturing and marketing of the improvement, resort to such changes therefrom, as do not depart from the spirit of the invention as defined by the appended claims.

Having described the invention, I claim:—

1. A coal wagon having the sides and front of its bottom inclined toward the center thereof, and the said bottom being arranged at an inclination from the front to the rear thereof, an end gate hinged to the top of the wagon body having its lower edge complementary to the bottom of the wagon, said end gate having a central opening, a hinged door closing the opening and a depending tongue on the door, means operable for simultaneously locking the door and end gate and for independently releasing the door and end gate, and said means including a spout for directing the load from the wagon body.

2. A coal wagon having the bottom at the front and sides thereof inclined downwardly toward the center and the said bottom being

also inclined from the front to the rear thereof, an end gate hinged to the top of the wagon body having its lower edge complementary to the bottom of the body, said end gate having a central opening, a door therein having its upper edge hinged to the end gate, its lower edge projecting beyond the end gate and provided with a depending tongue, pockets in the rear of the wagon receiving the extending end of the door and the gate, a spout, a body plate therefor including upstanding fingers, guide means for the fingers and plate, and lever operated means for moving the plate and spout whereby to cause the release of the tongue when moved to one position without releasing the end gate, to permit of the release of the end gate when moved to a second position, and to lock both the door and end gate when moved to a third position.

3. A coal wagon having the sides and forward end of its bottom inclined toward the center thereof and the said bottom in-

clined from the front to the rear thereof, an end gate pivoted to the top of the wagon body having its lower edge complementary to the bottom of the body, said gate having its lower edge centrally provided with an opening, a door closing the same and having its upper edge hinged to the end gate, means on the rear of the wagon susceptible to movement for locking both the door and end gate and for permitting the independent opening of the door and end gate, said body having compartments at the rear thereof opening at the sides and to the bottom of the body, doors hinged to the center of the bottom and movable in the compartments to close the same, latching means for the doors which, when released, permit of the doors being swung at downward inclinations, and slideable closures for the open outer ends of the compartments.

In testimony whereof I affix my signature.

FRED ALBERT.
